UNITED STATES PATENT OFFICE.

JOHN G. BAUER AND JACOB M. BAUER, OF LAWRENCEBURG, INDIANA.

DESIGN FOR A BARREL-HOOP.

SPECIFICATION forming part of Design No. 28,704, dated May 24, 1898.

Application filed October 23, 1897. Serial No. 656,213. Term of patent 14 years.

To all whom it may concern:

Be it known that we, JOHN G. BAUER and JACOB M. BAUER, citizens of the United States, residing at Lawrenceburg, in the county of Dearborn and State of Indiana, have invented and produced a new and original Design for Barrel-Hoops; and we do declare the following to be a full, clear, and exact description of the same, reference being had to the accompanying drawing, forming a part thereof.

The drawing is a perspective view of a barrel-hoop, showing our new design.

As shown, the leading or material feature of our design consists in a circular or annular hoop 1, having flattened or plane surfaces and having a widened or laterally-expanded and orificed portion 2. As shown in the drawing, said widened or laterally-expanded portion 2 is made with a flattened or plane surface and its opposite edges or margins are

curved, as indicated at 3 3, said curved edges meeting and joining with the edges of the main portion of the circular hoop at the ends of the said widened portion. The orifice 4 of the said laterally-expanded or widened portion 2 is, as shown in the drawing, centrally arranged and circular in contour. 25

Having thus described our new design, what we claim, and desire to secure by Letters Patent, is—

The design for a barrel-hoop, substantially as herein shown and described. 30

In testimony whereof we affix our signatures in presence of two witnesses.

JOHN G. BAUER.
JACOB M. BAUER
